[57] **ABSTRACT**

A friction shoe construction for a pivoting type window or closure. The window includes a sash which is mounted for pivoting movement with respect to the frame. The central portions of the sash stiles are pivotally connected to the jambs of the frame by arms, while the ends of the sash stiles are pivotally connected to shoes which ride in guide tracks on the frame jambs. Each shoe is constructed of a flexible material and is provided with a central opening having converging side walls. A wedge block having complementary inclined sides is mounted within the opening. A stud is connected to the wedge block and by tightening down the stud, the wedge block is moved within the opening in the shoe to force the sides of the shoe outwardly into engagement with the guide track to increase the frictional resistance.

FRICITION SHOE CONSTRUCTION FOR A PIVOTING WINDOW

The invention relates to a pivoting type window or closure and more particularly to an improved friction shoe construction for use with a pivoting type window.

In a pivoting type window the sash is mounted to tilt or pivot in a vertical direction with respect to the frame between the open and closed portions. In the conventional pivoting type window the central portions of the stiles of the sash are pivotally connected by arms to the jambs of the frame, and when the sash is in the closed position the arms are parallel to the jambs. In addition, the ends of the sash stiles are pivotally connected to shoes which ride within guide tracks in the frame jambs as the sash is pivoted between the open and closed positions. When the sash is in the closed position each shoe is located at the end of the respective track, and as the sash is pivoted to the open position, the shoe will slide towards the central portion of the track.

In order to hold the sash at any desired open position, a friction mechanism is normally associated with one or both of these shoes, which will provide sufficient frictional resistance between the shoe and the guide track to prevent free return of the sash by gravity to the closed position. In the past, the friction mechanisms have taken various forms. However for the most part the friction mechanisms of the prior art have been difficult to adjust in that the location of adjustment was in a relatively inaccessible location. Furthermore, in some situations special tools were required to provide the adjustment.

As a further disadvantage, the conventional friction devices have relied on spring pressure so that the frictional resistance was limited to the spring force. Therefore, with the use of a spring it was not possible to adjust the spring force to a degree so that the sash would be locked or frozen at a given position.

The present invention is directed to an improved friction shoe construction for a pivoting type of window or closure. According to the invention the shoe is formed of a flexible plastic material and the central portion of the shoe is provided with a generally trapezoidal shape opening in which the sides of the opening converge toward each other. Located within the opening is a wedge block having inclined sidewalls which complement the sides of the shoe bordering the opening. A stud, which is parallel to the guide track, extends through the end of the shoe and is engaged with the wedge block. By threading down the stud, the wedge block will be moved within the opening to thereby deflect the sides of the shoe outwardly by a wedging type of action and increase the frictional resistance of the sides of the shoe against the sidewalls of the guide track.

The friction shoe construction of the invention is a simple and inexpensive construction in which the frictional resistance can be readily varied by merely tightening or loosening the stud attached to the wedge block. The head of the stud is in an accessible location and no special tools, other than a screwdriver, are required to vary the frictional resistance.

As the frictional resistance is not dependent upon spring force, the frictional resistance can be increased to a point where the shoe will lock or freeze to the guide track, thereby preventing movement of the sash with respect to the frame. This feature is important when dealing with larger windows containing insulating type glass for the sash can weigh 100 pounds or more. Thus it is desirable to be able to lock the sash in a given position for window washing operations and the like.

Other objects in advantage will appear in the course of the following description.

The drawings illustrate the best mode presently contemplated of carrying out the invention.

In the drawings:

FIG. 1 is a perspective view of a pivoting type window incorporating the friction shoe of the invention.

FIG. 2 is a transverse section taken through the jamb of the frame and showing the sash in the closed position.

FIG. 3 is a fragmentary plan view showing the friction shoe.

FIG. 4 is an exploded view of the friction shoe, and

FIG. 5 is a fragmentary view showing the connection of the friction shoe to the sash.

The drawings illustrate a window 1 which includes a frame 2 and a sash 3 which is adapted to pivot with respect to the frame between an open and closed position. The sash can be locked to the frame by a conventional locking mechanism actuated by the handle 4.

Each jamb of the frame 2 defines a vertical guide track 5 which is bordered by the side members 6 and 7 of the frame.

5 10 A pivot hinge mechanism, indicated generally by 8, is employed to connect the sash 3 to the jambs of the frame 2. Each pivot hinge mechanism 8 includes an arm 9 which is pivotally connected by pivot 10 to a bracket 11 mounted by screws 12 to the track 5 of the frame jamb. The opposite end of the arm 15 9 is connected to the central portion of the stile 13 of the sash by a pivot 14. When the sash is in the closed position, the arm 9 will be located parallel to the track 5 and as the sash is pivoted to the open position the arm will pivot to an angular position as shown in FIG. 1 and FIG. 3.

20 In addition to the pivot hinge mechanism, the ends of the sash stiles are pivotally connected to shoes 15 which are adapted to ride within the tracks 5. A pin 16 is journaled for rotation within an opening in each shoe 15 and is received within a cylindrical channel 17 formed in the upper rail of the sash. As shown in FIG. 6 a spring 18 bears against the end of the pin and urges the shoe 15 towards the bottom of the track 5. A portion of the cylindrical channel 17 is bent inwardly as indicated by 19 to retain the spring 18 in position. The spring 18 functions during assembly to maintain a shoe in the bottom 30 of the track. Once the sash of the shoe has been assembled the spring 18 performs no function during the normal opening and closing of the sash.

35 As best illustrated in FIGS. 3 and 4, the shoe 15 is provided with a central generally trapezoidal shaped opening 20 with the walls 21 bordering the opening 20 converging towards each other. The shoe 15 is preferably formed of a relatively hard, yet flexible, plastic material, such as nylon, which has self lubricating properties so that it will slide smoothly within the track 5.

40 45 Mounted within the central opening 20 is a wedge block 22 having tapered sidewalls 23 which complement the tapered walls 21. To move the wedge block 22 within the opening 20, a stud 24 extends through aligned openings 25 and 26 in the shoe 15 and block 22, respectively, and engages a nut 27 located within a slot 28 in the block. The end of the shoe is provided with a recess 29 which receives the head 30 of the stud so that the head does not protrude beyond the surface of the shoe.

50 55 By threading the stud 24 downwardly within the nut 28, the wedge block 22 will be drawn towards the narrow end of the opening 20 to thereby deflect the sides 31 of the shoe outwardly and force the sides 31 into tight bearing engagement with the side members 6 and 7 of the track. The portion of the shoe extending between the surface 21 and the side 31 is sufficiently thin so that the wedging action provided by the block 22 can deflect or deform the side 31 outwardly into engagement with the side members 6 and 7 of the track.

60 The head 30 of the stud 24 faces downwardly toward the bracket 11 and is in a readily accessible position where it can be adjusted by means of a screwdriver. By merely turning the adjusting stud or screw the frictional resistance between the shoe 15 and the side members 6 and 7 of the track can be conveniently varied as desired. As the frictional resistance is not dependent on spring force, the stud 24 can be tightened down to a degree such that the frictional resistance is increased to a point where the shoe 15 will lock against the side members 6 and 7 of the track to prevent any pivotal movement of the sash with respect to the frame. This latter feature is of importance

65 when dealing with large, double glazed windows in which the sash can be of substantial weight, for it is frequently desired to lock the sash in a given position during window washing operations, repair or the like.

70 75 While the above description is directed to a window it is contemplated that the friction shoe construction can be used

for any type of pivoting type closure such as ventilator, door, cover, manhole, or the like.

Various modes of carrying out the invention are contemplated as being within the scope of the following claims particularly pointing out and distinctly claiming the subject matter which is regarded as the invention.

I claim:

1. In a sliding pivot closure structure having a sash pivotable with respect to a frame, a track formed in a jamb of the frame and including a pair of parallel side members, a sliding shoe mounted for sliding movement in the track, a shaft rotatably mounted in said shoe and connected to said sash, said shoe being provided with a central opening with the surfaces of the shoe bordering said opening converging longitudinally of the direction of sliding movement of the shoe in said track, a wedge block disposed within the opening and having converging sidewalls to complement the converging surfaces of said shoe, and operating means operably connected to said block for moving the block longitudinally within the opening with

movement of said block towards the converging ends of said surfaces serving to deflect the sides of the shoe outwardly into tight bearing engagement with the side members of the track to thereby increase the frictional resistance between said shoe and said side members.

2. The structure of claim 1, wherein said operating means comprises an operating member extending through an opening in the shoe and engaged with said block, said operating member extending longitudinally of said track with an end of the operating member being exposed at the end of the shoe.

3. The structure of claim 2, wherein said wedge block is provided with a slot extending in a plane transverse to the direction of sliding movement of the shoe, and said structure includes a nut located within the slot, said operating member comprising a stud threadedly engaged with the nut.

4. The structure of claim 3, wherein the end of the shoe is provided with a recess to receive the head of the stud.
